COMBINED CALENDAR AND CALENDAR HOLDER

Samuel Tylon, Cleveland, Ohio

Application September 16, 1952, Serial No. 21,485

Term of patent 14 years

(Cl. D74—5)

To all whom it may concern:

Be it known that I, Samuel Tylon, a citizen of the United States of America, residing at Cleveland, in the county of Cuyahoga and State of Ohio, have invented a new, original, and ornamental Design for a Combined Calendar and Calendar Holder, of which the following is a specification, reference being had to the accompanying drawing, forming a part thereof.

In the drawing:

Figure 1 is a front elevational view of a combined calendar and calendar holder showing my new design, as it appears in position for hanging;

Fig. 2 is a side elevational view thereof as it appears in supported position; and

Fig. 3 is a rear elevational view of the com-

bined calendar and calendar holder shown in Fig. 1.

I claim:

The ornamental design for a combined calendar and calendar holder, as shown.
